FLUSHING APPARATUS

William G. Merritt, Alameda, Calif.

Application December 14, 1945, Serial No. 635,125

7 Claims. (Cl. 137—145)

(Granted under the act of March 3, 1883, as amended April 30, 1928; 370 O. G. 757)

1

This invention relates to flushing apparatus and more particularly to apparatus for flushing radiators, oil coolers, or other circulation systems or the like with cleansing fluids.

Objects of the invention are to provide improved flushing apparatus for directing flow of cleansing fluids through circulation systems or the like, by use of which the direction of flow through the systems may be periodically automatically reversed; to provide flushing apparatus of the character referred to in which the period of reversals may be varied as desired; to provide improved mechanisms for reversing the direction of flow of fluids; and to provide for carrying out the foregoing objects in a facile, economical, and efficient manner.

In accomplishing these and other objects of the present invention, I have provided improved details of structure, the preferred forms of which are illustrated in the accompanying drawings; wherein:

Fig. 1 is an end elevational view of a flushing apparatus embodying the features of the present invention.

Fig. 2 is a vertical sectional view of the apparatus taken substantially on the line 2—2 of Fig. 1.

Fig. 3 is a horizontal sectional view of a portion of the apparatus taken substantially on the line 3—3 of Fig. 1.

Fig. 4 is a vertical sectional view of a modified form of the apparatus.

Referring more in details to the drawings:

In the form of my invention illustrated in Figs. 1, 2 and 3, the apparatus comprises a first manifold 1 and a second manifold 2, secured together and operatively connected by a pair of conduits 3 and 4, the manifolds and conduits preferably being formed of cylindrical metallic pipe sections secured together, as by welding. The conduits 3 and 4 are preferably joined to the second manifold 2 adjacent the ends of the latter. The first manifold preferably has a strainer or filter 5 removably secured to its lower or discharge end as by a collar 6.

An inlet connection 7 is secured to the manifold 2 midway of the length of the latter and normally the apparatus is supported from a pipe secured to said inlet connection, although it is obvious that other support means could be provided. A pair of discharge connections or distribution ports 8 and 9 (Fig. 1) are secured to the manifold 2 at each side of said inlet connection and are substantially equally spaced longitudinally therefrom.

2

When water is employed as the cleansing fluid, the inlet connection 7 is secured to any convenient water carrying line or pipe, not shown, which furnishes a supply of water under pressure, as well as serving to support the apparatus. When the cleansing fluid employed is other than water, as, for example, some suitable solvent, the inlet connection may be connected to a tank or other supply of fluid, with a suitable pump being provided for forcing the fluid through the apparatus.

The distribution ports 8 and 9 are adapted to communicate with inlet and outlet openings of a circulation system or the like, not shown, to function alternately to carry fluid to the system and to return fluid to the manifold, in a manner hereinafter explained.

Effluent from the apparatus passes therefrom through the strainer or filter 5. When the cleansing fluid is water, the effluent is ordinarily discarded after it leaves the apparatus. When fluid other than water is employed, the effluent is normally returned to the tank or other source, after having been cleaned as much as practicable, to thus complete a fluid circuit.

As shown in Fig. 2, a pair of longitudinally spaced pistons 10 and 11 are slidably mounted in the manifold 2 for reciprocable movement between lowered and raised positions, the lowered position being illustrated in Fig. 2. The pistons 10 are secured to a common piston rod 12 and the longitudinal distance between the pistons is preferably approximately equal to the distance between the centers of the distribution ports 8 and 9. The piston rod 12 extends outwardly from the manifold from an end thereof through a stuffing box 13, which may be of any suitable known construction, as, for example, that illustrated.

Preferably stop means are employed to limit sliding movement of the pistons. The stop means may conveniently comprise an extension 14 beneath the lower piston 10 engageable with the bottom wall of the manifold 2 to limit downward movement of the pistons and a sleeve 15 fixed to the piston rod above the upper piston 11 engageable with the stuffing box to limit upward movement. It is apparent that other stop means could be employed and would be full equivalents; for example, a system of collars as employed in the modified form of the invention shown in Fig. 4 and described hereinafter could be used.

An actuating cylinder 16 is supported on the manifold 2 by means of a pair of conduits 17 and 18, which preferably are connected to the manifold longitudinally adjacent the distribution ports 8 and 9 and to the cylinder adjacent the

ends thereof. The conduits 17 and 18 preferably are equipped with flow regulating means 19 and 20, respectively, which are operable to adjust the periods of reversals of flow through the apparatus in a manner hereinafter explained. The regulating means may be any suitable known type of adjustable regulatory valves.

A double acting actuating piston 21 is slidably mounted for reciprocable movement in the cylinder 16 and is connected to a piston rod 22. The latter extends outwardly from the cylinder from an end thereof through a stuffing box 23 that likewise may be of any suitable known construction. The piston rods 12 and 22 extend from the manifold and cylinder respectively in spaced parallel relation to each other.

A beam 24 is fixed between the manifold 2 and the cylinder 16 and an upright 25 is fixedly secured to said beam and extends in spaced parallel relation to the piston rods 12 and 22 substantially midway between them. The upright preferably has a guide bar 26 fixedly secured to its upper end, and said guide bar is apertured to slidably receive the piston rods and thus guide their movement.

Intermediate of their lengths the piston rods 12 and 22 carry guides 27 and 28, respectively, which are preferably substantially identical in construction. The guides each comprise end pieces fixed to the rod sections and spaced parallel side plates fixed to the end pieces. Preferably a pair of spaced upper and lower rollers 29 are rotatably mounted between the side plates of each guide.

A pair of arms 30 and 31 are pivotally connected to the upright 25 and engage the guides 27 and 28 respectively. As shown most clearly in Fig. 3, the arm 30 is preferably bifurcated, as indicated at 32, to provide portions for embracing the upright 25 and a similar bifurcation on the arm 31. The outer end of the arm 30 has a central extension 33 that is slidably received between the side plates of the guide 27 and between the rollers 29. The arm 30 also has a pair of external extensions 34 and 35 that engage the external surfaces of the side plates of the guide. The arm 31 is preferably substantially identical in construction to the arm 30 and hence is not described in detail.

As shown in Figs. 2 and 3, the outer external extensions of the arms 30 and 31 have studs 36 and 37 respectively fixed thereto. A pair of tension springs 38 and 39 are connected between the studs 36 and 37 preferably on each side of the arms.

Operation

The inlet 7 is connected to a suitable source of cleansing fluid and the distribution ports are connected to access openings of a radiator or other circulating system or the like to be flushed.

Fluid enters the manifold 2 through the inlet 1 between the pistons 10 and 11. With the pistons in the lowered position, as illustrated in Fig. 2, fluid discharges from the manifold through the lower distribution port 8, whence it passes through the system being flushed and returns to the manifold through the upper distribution port 9. After returning to the manifold 2, the fluid leaves through the conduit 4 and passes into the manifold 1, from which it emerges through the strainer 5.

As fluid leaves the manifold 2 through the distribution port 8, a smaller amount of fluid enters the actuating cylinder 16, below the double

5 acting piston 21, by way of the valved conduit 17. As the cylinder is gradually filled, the piston 21 is forced upwardly, thus raising the piston rod 22 and the guide 28. Upward movement of the guide pivots the arm 31 in a counterclockwise direction, as viewed in Fig. 2, thus extending the springs 38 and 39.

Such movement continues until the arm 31 becomes aligned with the arm 30 and moves a little beyond the aligned position. When such relative position is reached, the springs 38 and 39, acting on the arm 30, pivot the latter in clockwise direction as viewed in Fig. 2. The arm 30 acts on the guide 27 to raise the guide and thereby raise the piston rod 12 and the pair of pistons 10 and 11.

The direction of flow of fluid from the manifold 2 is thereby reversed, since, in the raised position of the pistons, fluid may be discharged from the manifold through the upper distribution port 9, but not through the lower distribution port 8. The fluid now returns to the manifold 2 through the lower distribution port 8 and passes therefrom into the manifold 1 by way of the conduit 3.

As fluid is discharged from the upper opening 9, a smaller amount thereof flows through the upper valved conduit 18 into the actuating cylinder 16 above the piston 21. Such fluid acts on 30 the piston to lower it, and thereby lower the piston rod 22 and the guide 28 and pivot the arm 31 in a clockwise direction as viewed in Fig. 2. When the arm 31 is pivoted past alignment with the arm 30, the springs 38 and 39 again act 35 on the arm 30, this time to pivot the arm in a counterclockwise direction as viewed in Fig. 2. Such pivoting of the arm 30 lowers the guide 27, the piston rod 12, and the pair of pistons 10 and 11. The direction of flow is thus again reversed.

10 The cycle of reversals of direction of flow just described continues as long as desired.

The period of reversals may be varied by adjusting the regulating valves 19 and 20, which control the volume of fluid permitted to flow through the valved conduits. It is seen that the greater the flow of fluid into the actuating cylinder, the more frequently the reversals occur. If it is desired to have flow from the manifold in one direction only, the regulatory valves may be closed, thus preventing flow into the actuating cylinder.

Modification

In Fig. 4 I have shown a modified form of flushing apparatus embodying the features of the present invention in which only a single manifold is employed.

The modified form of apparatus comprises a manifold 40, having an inlet connection 41 and a pair of discharge openings or distribution ports, not shown, but arranged similarly to the distribution ports 8 and 9 in the form of the apparatus shown in Figs. 1, 2 and 3. A strainer or filter 42 is preferably removably secured to the lower end of the manifold.

65 A pair of longitudinally spaced pistons 43 and 44 are slidably mounted in the manifold for reciprocable movement between lowered and raised positions, the lowered position being illustrated in Fig. 4. The pistons are joined by a tubular connector member open at each of its ends to the manifold outside of the pistons.

70 A piston rod 46 is secured to the upper piston 44, by means of a spider 47, and extends outwardly of the manifold through a suitable stuffing

box 48. The piston rod carries stop means, preferably a pair of spaced collars 49 and 50, engageable with the sides of the stuffing box, for limiting movement of the pistons.

The modified form of the apparatus comprises flow reversing means, designated generally as 51, which is identical to the means shown and described in connection with the embodiment of the invention of Figs. 1, 2 and 3; hence the means is not described in detail in connection with the modified form of the invention.

The operation of the modified form of the apparatus is substantially similar to the operation already described, except that fluid returning to the manifold 40 through the upper distribution port passes into the lower portion of the manifold through the tubular member 45. Such fluid, as well as fluid returning to the manifold through the lower distribution port, is drained from the manifold through the strainer 42.

While I have shown but certain embodiments of my invention, it is apparent that the device is susceptible to further modification without departing from the spirit of the invention. I do not wish, therefore, to be limited by the disclosures set forth, but only by the scope of the appended claims.

The invention described herein may be manufactured and used by or for the Government of the United States of America for governmental purposes without the payment of any royalties thereon or therefor.

I claim:

1. A device of the character described comprising a manifold having an inlet, a distribution port, a conduit opening thereinto, and an outlet; a piston slidable in said manifold past said distribution port and the conduit opening between a first position wherein said distribution port and said conduit opening are in fluid communication directly through said manifold with said outlet and are blocked from fluid communication directly through said manifold with said inlet and a second position wherein said port and said conduit opening are in fluid communication directly through said manifold with said inlet and are blocked from fluid communication directly through said manifold with said outlet; said manifold having, also, a second distribution port, a second conduit opening thereinto, and a second outlet all disposed in the portion of said manifold axially opposite, relative to said inlet, to the portion containing their corresponding first mentioned counterparts; a second piston slidable in said manifold past said second port and the opening of said second conduit between a first position wherein said second port and said second conduit opening are in fluid communication directly through said manifold with said inlet and are blocked from fluid communication directly through said manifold with said second outlet and a second position wherein said second port and said second conduit opening are in fluid communication directly through said manifold with said second outlet and are blocked from fluid communication directly through said manifold with said inlet; means connecting said pistons to move together so that each assumes its respective first position substantially simultaneously with the other and each assumes its respective second position simultaneously with the other; an actuating cylinder having an actuating piston slidably disposed therein; said actuating cylinder having said conduits connected thereto, one open-

ing thereinto on either side axially relative to said piston; means in said conduits for controlling the flow of fluid therein; means including a yieldable linkage connected between said actuating piston and said manifold pistons whereby movement of said actuating piston in opposite directions produces movement of said manifold pistons between their first and second positions.

2. In a flushing apparatus, a manifold having an inlet midway of the length thereof and a pair of distribution ports spaced longitudinally from said inlet at each side thereof, a pair of connected pistons having their adjacent faces spaced apart a distance greater than the distance between the inlet and either distribution port, said pistons being slidable in said manifold between positions spanning said inlet and first one and then the other of said distribution ports, a piston rod secured to said pistons and extending beyond said manifold, an actuating cylinder, conduits connected to said manifold opposite said distribution ports and to said cylinder adjacent the ends thereof, an actuating piston slidable in said cylinder, means for venting fluid from that side of said actuating piston opposite the side thereof being supplied by fluid from one of said conduits, a piston rod secured to said actuating piston and extending in parallel relation to said first named rod, guide means carried by said piston rods, support means carried by said manifold and cylinder, arms pivoted to said support means and slidable in said guide means, and spring means connecting said arms, whereby movement of said actuating piston beyond predetermined points moves said first named pistons to change direction of flow from said manifold.

3. In a flushing apparatus, a manifold having an inlet midway of the length thereof and a pair of distribution ports spaced longitudinally from said inlet at each side thereof, a pair of pistons slidable in said manifold and having their adjacent sides spaced apart sufficient to span said inlet and either of said distribution ports, tubular means connecting said pistons and being open at the ends outwardly of the pistons, a piston rod secured to said pistons, an actuating cylinder, conduits connected to said manifold opposite said discharge openings and to said actuating cylinder adjacent the ends thereof, an actuating piston slidable in said cylinder, a piston rod secured to said actuating piston, and spring and linkage means operatively connecting said piston rods whereby movement of said last piston beyond predetermined points moves said first named pistons to change direction flow from said manifold, said manifold having a drain adjacent an end thereof.

4. A device of the character described comprising a cylinder having an inlet, an outlet connection, and a pair of distribution ports; a pair of spaced pistons slidable as a unit within said cylinder between a first position in which said pistons place the first of said ports in fluid communication with said inlet and the second of said ports in fluid communication with said outlet connection and a second position in which said pistons place said second port in fluid communication with said inlet and said first port in fluid communication with said outlet connection; and mechanism actuated by fluid supplied from said inlet for periodically automatically shifting said pistons to and from said positions, said mechanism comprising an actuating cylinder and piston, a pair of fluid conduits each having its one

end connected to said actuating cylinder one on either side of said actuating piston, said conduits being connected at their other ends each to partake, respectively, of the fluid flow in the same manner as one of said distribution ports, and means connecting said actuating piston with said spaced pistons whereby motion of the former is transmitted to the latter.

5. The device of claim 4 wherein said last named means includes a toggle linkage whereby said spaced pistons are shifted suddenly between their limiting positions.

6. A device of the character described comprising a cylinder having an inlet, an outlet connection, and a pair of distribution ports; a pair of spaced pistons slidable as a unit within said cylinder between a first position in which said pistons place the first of said ports in fluid communication with said inlet and the second of said ports in fluid communication with said outlet 20 connection and a second position in which said pistons place said second port in fluid communication with said inlet and said first port in fluid communication with said outlet; and mechanism actuated by fluid supplied from said inlet for periodically automatically shifting said pistons to and from said position, said mechanism comprising an actuating chamber and an actuating

member therein, a pair of fluid conduits connecting with said chamber on opposite sides of said member, one conduit being connected to transmit the fluid pressure at one of said ports and the other conduit being connected to transmit the fluid pressure at the other of said ports, and means linking said member to said spaced pistons.

7. The device of claim 4 wherein valves are provided in said fluid conduits.
